United States Patent Office.

THOMAS J. CHUBB, OF BROOKLYN, NEW YORK.

Letters Patent No. 67,498, dated August 6, 1867.

IMPROVEMENT IN AMALGAMATORS.

The Schedule referred to in these Letters Patent and making part of the same.

TO ALL WHOM IT MAY CONCERN:

Be it known that I, THOMAS J. CHUBB, of Brooklyn, in the county of Kings, and State of New York, have invented a new and improved Amalgamator; and I do hereby declare that the following is a full, clear, and exact description thereof, reference being had to the accompanying drawings, making a part of this specification, in which—

Figure 1 is an elevation of one side of the amalgamator.

Figure 2 is a view of one end of the amalgamator.

Figure 3 is a view of the opposite end of the same.

Figure 4 is a sectional side elevation.

Figure 5 is a sectional end view through line *x x*.

Figure 6 is a sectional end view through line *y y*.

Figures 7, 8, 9, 10, 11, and 12, of sheet 2, represent a modification of the conveyer and its chamber.

Similar letters of reference indicate corresponding parts in the several figures.

This invention relates to a mode of carrying out the process of amalgamation by the vapors of mercury, which formed the subject of my caveat, filed in the confidential archives of the Patent Office on the 29th day of June, 1854.

To enable others skilled in the art to understand my invention, I will describe its construction and operation.

In the accompanying drawings, A represents a revolving cylinder. B B are friction-rollers, on which the cylinder A is supported and caused to revolve. C C are shelves or elevators, which are arranged within the cylinder A. D is a conveyer-screw, to receive the ore and conduct it toward a conveyer-screw, E, which deposits the ore into the cylinder A. F is a conveyer-screw, to discharge the ore from the cylinder A at the opposite end to that in which the ore is fed into the cylinder. G is a receiving-hopper. H is a discharge-hopper. I is a discharge pipe, and J J are stationary pipes or casings for the conveyers D E F. K is a furnace, arranged within which is a retort or mercury-still, L. M is a pipe and globe-valve for charging the retort L with mercury. N is a discharge pipe, leading from the cylinder A to the retort L. O is a pipe for the discharge of the surplus vapor of mercury. P is a receiver for condensing this surplus vapor. Q is a cold-water chamber in the condenser P, and R is a pipe, connecting with the chimney V, or with a pump, to create a partial vacuum in the cylinder A, for the purpose of preventing the escape of mercury from said cylinder, or any of its connections where vapor of mercury will be contained. S S S are stuffing-boxes for the ends of cylinder A and casings J J. T is an outer casing that surrounds the entire apparatus, and forms a housing for the same. U is a flue or pipe or pipes, connecting the cylinder with the chimney V, with cold-water condenser attached. V is a safeguard, in case of any leak of mercury vapor from the cylinder A, or its connections and passages to the chimney. Z is a cover to the hopper G, which may be closed when it is not desired to feed ore into said hopper. X is the propelling-shaft for the conveyer, and W is a pulley and shaft for communicating motion to the cylinder A.

The operation of the apparatus is as follows: Dry pulverized ore is fed into the hopper G through the opening Z. The small conveyer D screws the ore from under the hopper G, and banks it up between D and E, thus preventing any outward passage of air or vapor at that point. When said space between D and E becomes overcharged the screw-threads E carry off the surplus, always leaving the upper half of said screws or chambers J J vacant, so as to leave a passage for the vapor in the upper half of chambers J J. The ore is thus conveyed into the cylinder A; and as this cylinder revolves the ore is carried up by the shelves C C, and caused to fall again in a loose state through the vapor of mercury therein. The ore works its way into the left-hand end of the cylinder A, and falls into hopper F, and is conveyed away, through the pipe I, into water, or any kind of box, machine, amalgamator, or other suitable receptacle. The amalgam should be allowed to settle in water, or be agitated in water, to collect it in a mass. The liquid mercury is fed into the retort L by and through the globe-valve, which is provided with stop-cocks, so that this retort can be charged at any time. Should gold amalgam be used in the retort, the gold will remain in the retort, and be taken out by opening the front end thereof, which may be made perfectly tight by means of clay or otherwise. The vapors pass into the cylinder A, and form an atmosphere of mercury, through which the dry ore is caused to continually fall. The mercury condenses on the gold or silver, coating the surfaces of the particles, so that such particles will adhere to each

other, and eventually, by agitation, will form one amalgamated mass; but it is preferable to allow the ore to pass out of the cylinder A as rapidly as all the particles of gold are sufficiently coated, and to aggregate the particles in a separate vessel of water.

In sheet 2 I have represented a modification of a part of the machine hereinabove described. For coarse ore this modification may be found advantageous. This plan shows the centre or inside cylinder, or casing for the stirring-conveyer, joined in the middle, and the revolving cylinder dispensed with, or allowed to remain stationary as a jacket, to keep the inner cylinder warm. This cylinder may be arranged on an incline, the discharging end being the lowest; and, if desirable, water may be admitted into this cylinder, near the lower end, for condensing the surplus vapor.

The apparatus above described may be used after the decomposing and oxidizing process, which forms the subject of another application for a patent made by me; or it may be used after a dry-crushing and grinding operation; or any pulverized ore thoroughly dry can be treated in this machine. Having thus described my invention, what I claim as new, and desire to secure by Letters Patent, is—

1. The employment of a revolving cylinder, in combination with lifters, stirrers, or agitators, for conveying and stirring ore containing precious metals, whilst such ore is being subjected to the action of the vapor of mercury, substantially as described.
2. The employment of a revolving shaft, with stirrers or projections on it, for stirring, conveying, and exposing ore containing precious metal, and while such ore is being exposed to the vapor of mercury, substantially as described.
3. The arrangement of a condenser, in combination with a mercury-still and contrivances for exposing the ore to the action of the vapor of mercury, substantially as described.
4. Producing a partial vacuum in a mercury-retort and appurtenances of an apparatus for amalgamating precious metals by means of a pump, chimney, or their equivalents, substantially as described.
5. The outer casing or housing for enclosing an apparatus in which the vapors of mercury are used for amalgamating precious metals, substantially as described.
6. Providing for collecting the vapor of mercury on its way from the amalgamator to the escape-flue or chimney, substantially as described.
7. Heating the amalgamating-chamber, in which the vapors of mercury and precious metals are contained, by heat applied upon the outside of the chamber, so as to prevent a too sudden condensation of the mercury upon the inside of said chamber.

THOS. J. CHUBB.
